CLAIM

The ornamental design for a gift card maze puzzle, as shown and described.

DESCRIPTION

FIG. 1 is a top perspective view of a gift card maze puzzle showing our new design;

FIG. 2 is a bottom perspective view thereof;

FIG. 3 is a top view thereof;

FIG. 4 is a bottom view thereof;

FIG. 5 is a right side view thereof; the left side view is a mirror images of the right side;

FIG. 6 is a back view thereof; and,

FIG. 7 is a front view thereof.

The broken line showing of the words “Puzzlerz!” and “OPEN” depicted on the bottom surface of the invention in FIGS. 2 and 4 is for illustrative purposes only and forms no part of the claimed design.

The gift card maze puzzle is designed to hold a gift card or money.
